SKYLIGHT

Morris Feldman, Philadelphia, Pa.

Application September 25, 1937, Serial No. 165,664

3 Claims. (Cl. 108—16)

This invention relates to skylights and is concerned particularly with a movement which is included in the construction of the skylight for the purpose of controlling opening and closing of the ventilating shutter of the skylight.

At the present time it is common practice in the art of skylights to mount a skylight frame that includes a ventilating shutter over an opening in a building structure to which the skylight is to be applied. Prior to the present invention it has been the practice to mount the movement for controlling operation of the shutter in the building structure defining the opening. As a result of this arrangement, inconvenience is experienced in obtaining a proper coordination between the skylight movement and the ventilating shutter and particularly in the installation of the skylight as an entirety.

With the foregoing conditions in mind, this invention has in view as its primal objective the provision of a skylight comprising a frame including a ventilating shutter, and which frame has mounted thereon a movement for controlling operation of the shutter. With this assembly the skylight in its entirety may be readily installed over any suitable opening with ease and facility.

Another somewhat more detailed objective of this invention is the provision of a skylight including a skylight movement of a simplified and improved character. In accordance with this invention, the movement which is mounted on the skylight frame includes a pulley carrying an endless chain as an operating member therefor. A crank arm is carried by the pulley and connected by a link with the ventilating shutter. In one dead center position of the crank arm and link the shutter is in a fully closed position, while in the opposite dead center position the shutter is fully extended.

Various other more detailed objectives and advantages will in part become apparent and in part be hereinafter stated, as the description of the invention proceeds.

The invention, therefore, comprises a skylight, comprising a frame adapted to be mounted over an opening in the building structure, and which frame includes a ventilating shutter. Carried by the frame itself is an improved movement for controlling opening and closing of the shutter.

For a full and more complete understanding of the invention reference may be had to the following description and accompanying drawings, wherein

Figure 1 is an elevational view of a skylight

frame made in accordance with the precepts of this invention.

Figure 2 is a showing viewed in the same direction, as Figure 1, but taken as a transverse section through the skylight. In this view the movement is shown in elevation and the opened position of the shutter brought out in dotted lines.

Figure 3 is a plan view of the movement per se. In this view the frame is broken away and shown in section,

Figure 4 is an elevational showing taken at right angles to the showing of Figure 3,

Figure 5 is a plan view of the link which is connected to the shutter, and

Figure 6 is a view taken at right angles to the showing of Figure 5.

Referring now to the drawings wherein like reference characters denote corresponding parts, the skylight frame of the type with which this invention is concerned is shown in Figures 1 and 2 as comprising end pieces 10 and 11. These end pieces 10 and 11 are made of sheet metal and are of duplicate construction, and each is formed with an inclined edge 12. This edge 12 is preferably defined by deforming the sheet metal of the end piece into a channel-like construction as shown in the drawings. This channel, as well as other channel constructions, to be hereinafter described, receive the edges of a pane of glass, 30 designated 13.

Each of the side pieces 10 and 11 is formed at the bottom with a straight edge which is defined by an offset structure designated 14. This structure 14 being preferably integral with the end piece.

At one side each of the end pieces 10 and 11 has a short side edge 15 connecting the inclined edges 12 with the straight edges 14, while these edges 12 and 14 are connected at the more widely spaced extremities by an upright edge 16 and an inclined edge 17.

The short side edges 15 of the end pieces 10 and 11 are connected together by a wall structure 18, while another wall structure designated 19 connects the inclined edges 17.

Secured on the inner side of each of the upright edges 16 and the side pieces 10 and 11 is a channel structure designated 20, and these channel structures 20 together with the structure 19 and a bottom offset structure 21, that corresponds to the structure 14, define an opening in which is pivotally mounted a ventilating shutter, designated 22.

This ventilating shutter 22 is pivotally mount-

ed as indicated at 23 to the channel structures 20 and at each side the shutter 22 is formed with a flange 24 that is spaced from the side edges of the ventilating structure, as by the flange 25. 5 This spaced flange 24 may be integral with the side flange 25 and connected thereto by a portion designated 26. When the shutter 22 is in a closed position, the spaced flanges 24 at each side of the shutter are received in the channels 10 of the channel structures 20.

The offset construction of the members 14 and 21 is carried out at the narrow side of the skylight as indicated at 27, and this structure is designed to fit over the frame of a building structure which 15 defines an opening, this practice being conventional in the building arts.

In the illustrated embodiment of the invention, the shutter 22 is shown as being made from a flat piece of sheet metal. Obviously, however, the invention contemplates similar constructions in 20 which the shutter is made of glass or other transparent material.

Referring now more particularly to the movement which controls opening and closing operations 25 of the shutter 22, a bracket as shown in Figures 2, 3, and 4 is designated 28. This bracket 28 is formed with diverging legs that terminate in feet 29 that are anchored to the channel member 20 that is adjacent to the side piece 11. Any 30 suitable means may be availed of to supply the anchorage, such as the bolt and nut arrangements illustrated at 30.

The legs of the bracket 28 come together and define a recess 31, through which passes a bearing pin 32. This bearing pin 32 passes through an opening in the end piece 11 and is headed as shown at 33. Carried by the bearing pin 32 is a pulley 34 that is retained in position on the bearing pin 32 by a cotter pin 35.

40 Extending diametrically across the pulley 34 is an arm 36 which preferably takes the form of the angle iron illustrated in the drawings. This arm may be affixed to the pulley 34 in any preferred manner as by the rivets shown at 37.

45 It is notable that at one end the arm 36 terminates at the periphery of the pulley 34, while at the other end the arm 36 projects beyond the periphery of the pulley 34 as shown at 38. This extension 38 is formed with an opening 39.

50 A bracket member 40 is anchored to the shutter 22 by a bolt and nut fastening assembly designated 41 and this bracket 40 is formed with a pair of spaced ears 42. A link member designated 43 has one end received between the ears 42 and is secured thereto by a pin 44 that is headed at one end and riveted at the other as 55 illustrated in the drawings.

The link 43 is formed with the offset portion 35 that is connected thereto by the portion designated 46 and the extremity of the offset portion 45 is formed with an opening 47. This opening 47 in the link structure is in alignment with the opening 39 in the extension of the arm 36, and extending between the aligned openings is a connecting pin designated 48, as shown in Figure 2.

60 The pulley 34 is formed with the usual channel or groove 49 and received in this channel or groove is an endless chain designated 50. This chain 50 extends downwardly to a conveniently accessible 70 position and may be availed of as an operating member for rotating the pulley 34 to open or close the shutter 22 as occasion demands.

75 When the shutter 22 is in the closed position illustrated in full lines by Figure 2, the offset portion 45 of the link 43 will engage against the

side flange of the angle iron, constituting the arm 36. It is obvious that further rotative movement of the pulley 34 in a counter-clockwise direction (speaking with reference to the showing at Figure 2) is prevented. However, when the pulley 34 is rotated in a clockwise direction, the arm 36 will be swung up and over into the dotted line position, forcing the link structure 43-45 upwardly to cause the shutter 22 to assume the dotted line position as illustrated in Figure 2. 10

Thus, it is evident that when the arm 36 is in one dead center position with respect to the link structure 43-45, the shutter 22 is in a fully closed position, whereas in the diametrically opposite dead center position of arm 36 and link structure 43-45, the shutter 22 will be in its maximum open position. 15

While a preferred specific embodiment of the invention is hereinbefore set forth it is to be clearly understood that I am not to be limited to the exact construction illustrated and described, because various modifications of these details may be provided in putting the invention into practice within the purview of the appended claims. 20

I claim:

1. A skylight structure of the character described, comprising a frame adapted to be mounted over an opening in a building structure, said frame including spaced end pieces, said frame also having a ventilating opening intermediate the end pieces, a shutter pivotally mounted in said opening, and a movement carried by one of the end pieces and operatively connected to the shutter for controlling opening and closing movement of the latter. 35

2. A skylight structure of the character described, comprising a frame including a rectangular bottom structure adapted to be positioned over a correspondingly shaped opening in a building structure, an end piece at each end of the bottom structure upstanding therefrom, each of said end pieces having an upright edge and an inclined edge, a connecting structure between the end pieces at the upper extremities of the inclined edges, said last mentioned connecting structure, bottom structure, and side pieces defining an opening, a ventilating shutter pivotally mounted in said opening, a skylight movement operatively mounted on one of the end pieces, and linkage connecting the movement with the shutter whereby operation of the movement causes operation of the shutter. 40

3. A skylight structure of the character described, comprising a frame including a rectangular bottom structure adapted to be positioned over a correspondingly shaped opening in a building structure, an end piece at each end of the bottom structure upstanding therefrom, each of said end pieces having an upright edge and an inclined edge, a connecting structure between the end pieces at the upper extremities of the inclined edges, a channel structure extending along the upright edge of each of the end pieces, said channel structures together with the bottom structure and upper connecting structure defining an opening, a ventilating shutter in said opening having offset flanges which are received in the channel structures when the shutter is in a closed position, a movement carried by one of the end pieces, means for operatively connecting the movement with the shutter and an operating member for said movement. 45
